(57) **CLAIM**

The ornamental design for an adjustable counterbalanced weight for a power washer wand, as shown.

DESCRIPTION

FIG. 1 is a perspective view of an adjustable counterbalanced weight for a power washer wand showing my new design;

FIG. 2 is a front view thereof;

FIG. 3 is a back view thereof;

FIG. 4 is a top view thereof;

FIG. 5 is a bottom view thereof;

FIG. 6 is a left side view thereof;

FIG. 7 is a right side view thereof;

FIG. 8 is a separated perspective view thereof;

FIG. 9 is a separated front view thereof;

FIG. 10 is a separated back view thereof;

FIG. 11 is a separated top view thereof;

FIG. 12 is a separated bottom view thereof;

FIG. 13 is a separated left side view thereof; and,

FIG. 14 is a separated right side view thereof.
